SILO DOOR CONSTRUCTION

Charles A. Bangert, Columbus, Ohio, assignor to
 Lamneck Products, Incorporated, Columbus,
 Ohio, a corporation of Ohio

Application April 13, 1936, Serial No. 73,996

8 Claims. (Cl. 20—1.4)

My invention relates to silo door construction. It has to do, more particularly, with silo unloading doors provided for concrete stave silos or the like although there are certain features of my invention not necessarily limited thereto.

5 The unloading doors of silos of the type indicated are usually locked in closed position by means of locks comprising ordinary bolts provided with handle nuts threaded thereon. Turnbuckles have also been used for this purpose. 10 After the door has been locked by such means for an appreciable length of time, the ensilage juices rust and corrode the threads on the locking means. Thus, when an attempt is made to open the doors, it is difficult or impossible to do 15 so.

The staves of concrete silos or the like are usually held in their proper positions by means of hoops or tie rods which encircle the silo. One 20 of these hoops is usually located at the top of the unloading doorway and another at the bottom of the doorway. However, in some cases an extra hoop or tie rod is disposed intermediate the above-mentioned hoops at a point substantially 25 midway between the upper and lower ends of the doorway. However, this hoop does not extend across the doorway so as not to interfere with entrance by a man into the silo through the doorway. This hoop has its free ends adjustably connected to the frame of the doorway at 30 opposite sides thereof. Obviously, this places considerable strain on the door frame which tends to cause the side members of the door frame to bulge outwardly.

35 One of the objects of my invention is to provide a novel type of lock for the unloading doors of silos which is of such a construction that it will not be rendered inoperative by corrosion or rust and may be quickly and easily unlocked at any time.

40 Another object of my invention is to provide means for use with concrete silos or the like adapted to be applied to the unloading doorway thereof for bracing the frame of the doorway in 45 such a manner as to prevent the strains to which it is subjected from causing distortion or bulging thereof.

The preferred embodiment of my invention is 50 illustrated in the accompanying drawing wherein in similar characters of reference designate corresponding parts and wherein:

Figure 1 is a perspective view of a concrete 55 stave silo having my invention applied thereto.

Figure 2 is an enlarged view in perspective of

the doorway and doors of the silo to which my invention is applied.

Figure 3 is a plan view of a novel lock which I preferably employ for locking the silo door in closed position. 5

Figure 4 is a horizontal section taken through the silo door and illustrating how the lock firmly holds the door in closed position.

With reference to the drawing, and particularly to Figure 1, I have illustrated a silo which is 10 made up of a plurality of vertically disposed concrete staves 1 which abut each other and are provided with interfitting edges. The staves are held in cooperative relation by means of a plurality of hoops 2 which extend entirely around 15 the silo and a plurality of tie rods 3 which extend the greater portion of the distance around the silo. This silo is shown as having a vertically disposed opening extending substantially from the top thereof to the bottom thereof which receives a door frame 4 illustrated best in Figure 2. This door frame serves as a means for mounting a plurality of doors to permit removal of the 20 ensilage from the silo.

The doorway 4 is made from a pair of vertically disposed metal beams 5 which are secured together by means of a plurality of transversely extending beams 6 which are disposed at vertically spaced intervals and are moved to correspond to the curvature of the wall of the silo. 25 The space between two adjacent beams 6 forms 30 The door 7 comprises mainly a steel plate which is hinged to the door frame 4 by means of a double hinge in such a manner that it may be swung inwardly 35 into the silo. This plate is curved transversely to correspond substantially to the curvature of the silo wall. The double hinge construction 40 comprises a plate member 8 pivoted to the frame as at 9 and to the door as at 10. This permits 45 the door to move bodily inwardly into the silo and when the door is closed permits the door to firmly contact with the door frame the entire distance therearound. The fact that the door and the door frame are curved transversely on 45 a radius corresponding substantially to that of the silo wall results in a closer fit at the top and bottom of the door frame.

In order to firmly hold the door in closed position and in such a manner that it may be readily 50 opened at any time, I provide novel locking means illustrated in Figures 2, 3 and 4. It will be noted that the outer surface of the door is provided with a pair of vertically disposed angle irons 11 55 welded or otherwise secured to the door. These

angle irons are so disposed that when the door is closed they are positioned close to the side members of the door frame. Adjacent the top and bottom of the door a transversely extending rod 12 is mounted on the angle irons so that it will be spaced from the surface of the door. These rods 12 may be sprung outwardly to a certain extent.

For cooperating with each of the rods 12 I provide a lock indicated generally by the numeral 13. This lock 13 embodies a lever 14 which is pivoted as at 15 to the transversely extending member 6 of the door frame. It will be noted from Figure 2 that the lock for the lower end 15 of the door is attached to the upper surface of the beam 6 while the lock for the upper end of the door is attached to the lower surface of the beam 6 adjacent thereto. The free end of the lever 14 serves as a handle by means of which the lock may be operated. At the pivoted end of the lever it is provided with an eccentric portion 16. This eccentric portion 16 has the outer end of a hook 17 pivoted thereto as at 18. The hooked end of the member 17 is adapted to fit around the rod 12, as indicated in Figure 2. It will be noted from Figures 3 and 4 that the pivot points 15 and 18 are out of alignment with each other, when the lever 14 is in locked and unlocked positions.

In the operation of this locking means, the door will be swung into closed position. The levers 14 of the locks will at this time be swung to the left (Figure 4). This will permit the members 17 to be hooked around the rods 12. To lock the door in position, it is merely necessary to swing the levers towards the right, as indicated in Figure 3. Swinging of lever 14 to the right will cause the pivot point 18 to move away from the door and, consequently, cause the hook 17 to pull on the rod 12. When the pivot point 18 is in alignment with the pivot point 15, the pivot point 18 will be at the farthest point it reaches from the front of the door. If the lever 14 is swung slightly farther towards the right or towards the door, the pivot point 18 will move out of alignment with the pivot point 15 and will be disposed at the right thereof. However, pivot point 18 will then move closer to the door. Thus, it will be apparent that during this swinging movement of the lever 14 into locking position it will be necessary for the rod 12 to bend sufficiently for the pivot point 18 to move rearwardly and to the right of the pivot point 15. As soon as the pivot point 18 moves to the right past the pivot point 15, the spring force of the rod 12 will cause the outer end of the lever to quickly snap against the rod 12. The outer end of the lever 14 is provided with a depending lug 19 for contacting with the rod 12 to limit swinging movement of the lever 14 towards the door. The lever 14 will be held in locked position by the spring force of the rod 12, until it is actually pulled outwardly and towards the left with sufficient force to overcome the spring force of the rod 12. During movement of lever 14 into locking position the hook 17 will automatically adjust itself along rod 12.

The hook 17 is of such a length that during the swinging movement of the lever 14 from unlocked position to locked position, the rod 12 will be sprung outwardly, it being sprung outwardly to the greatest extent when the pivot point 18 is at the farthest point from the door it reaches which will be at the time it is in alignment with the pivot point 15. However, when

the pivot point 18 moves to the right of the pivot point 15 and, therefore, slightly closer to the door, the rod 12 is still sprung outwardly. Consequently, this produces the spring force that causes the lever 14 to snap into locked position against the rod 12. It also causes the edges of the door to be in firm contact with the frame, as indicated best in Figure 4.

It will be apparent that the lock which I have provided is of such a type that there is no danger of rusting or corrosion preventing operation thereof. No portion of the lock extends through the door into the interior of the silo. Consequently, there is no danger of the ensilage juices affecting the lock.

As previously stated, the hoops 2 extend entirely around the silo. A saddle 20 is provided on each of the members 6 of the door frame for receiving one of the hoops 2. It will be noted that the hoops 3 extend the greater portion of the distance around the silo but do not extend across the doorway so as not to interfere with entrance of a man into the silo through the doorway. The hoops 3 are located substantially midway between the hoops 2 and, consequently, substantially midway between the upper and lower ends of each doorway. The free ends of the hoops 3 are adjustably secured to bracket members 21 and 22 which are bolted to the side members 4 of the door frame.

In order to prevent pulls on the free ends of the hoops 3 from producing strains on the side members 4 of the door frame I provide a structure which in effect serves to connect the ends of the hoop 3 together. This means is illustrated as comprising a rod 23. One end of this rod fits into an open-ended slot 24 formed in the bracket 21 and it has a head 25 formed on this end which normally prevents the bolt from slipping through the slot 24. The opposite end of the rod 23 passes through a slot 26, having its ends closed, which is formed in the bracket 22. It will be apparent that a portion of this bracket 22 having the slot 26 formed therein is bent into substantially horizontal position as at 27. Thus, part of the slot 26 is in a horizontal portion 27 and the other part of the slot is in a vertical portion 28 of the bracket 22. This end of the rod 23 has a nut 29 threaded thereon which normally prevents pulling of the end of the rod 23 through the slot 26.

When this rod 23 is in use, it is in the position indicated in Figure 2 at the top thereof. Thus, it serves as a connection between the two ends of the tie rod or hoop 3. It may be adjusted to prevent any strains being placed on the side members 4 of the door frame by reason of the connection of the ends of the member 3 thereto. It is merely necessary to tighten nut 29 to prevent any such strains being transmitted to the side members 4. When the door is opened and it is desirable for a man to enter the silo through the doorway, the rod 23 may be moved to inoperative position where it will not interfere with passage through the doorway. To do this the nut 29 is loosened. Then the opposite end of the rod 23 may be swung upwardly out of the slot 24. The rod may be swung into vertical position and then dropped through the slot 26 until the head 25 thereof rests against the horizontal portion 27 of bracket 22, as indicated in the lower portion of Figure 2. Thus, the rod will hang at one side of the doorway where it will not interfere with passage through the doorway. When the door is closed and it is desirable for the

rod 23 to again function, it is merely necessary to pull it vertically through the slot 26 and then swing it downwardly across the doorway until its one end falls into the slot 24.

5 It will be apparent that this rod 23 serves in effect to connect the ends of the member 3 and, therefore, prevents strains of the side members of the door frame. However, the rod 23 may be used even though a hoop member 3 is not disposed 10 between the hoop members 2. In some instances, the hoop members 3 are not employed. However, other forces tend to throw the door frame out of shape and this rod 23 will aid in preventing distortion of the door frame. The rods 15 23 serve another purpose. They serve as rungs to form a ladder along the doorway. The hoops 2 serve as rungs and the rods 23 located therebetween, also serve as rungs.

It will be apparent from the above that I 20 have provided effective means for locking a silo door which is of such a nature that corrosion or rusting will not prevent operation thereof. Furthermore, the lock is so located and constructed that it will be impossible for the ensilage juices 25 in the silo to affect it. I have also provided means for preventing strains on the frame of the doorway from causing bulging or distortion thereof.

Various other advantages will be apparent from the preceding description, the drawing, and the 30 following claims.

Having thus described my invention, what I claim is:

1. In combination a silo door movable between open and closed positions relative to a door frame, means for locking the door in closed position and in firm contact with the door frame, said means comprising a pivoted lever, a hook member pivoted to said lever at a point spaced from the pivot point of the lever, said hook member 35 being adapted to hook over a resilient rod mounted on said door, the pivot point of said hook to the lever being located at one side of the pivot point of the lever when the lever is in unlocking position and being located at the opposite side of the pivot point of the lever when the lever is in locking position, said hook member being of such length that said rod will be sprung when the lever is in locking position.

2. In combination a silo door movable between 50 open and closed positions relative to a door frame, means for locking the door in closed position and in firm contact with the door frame, said means comprising a pivoted lever, a connecting member pivoted to said lever at a point spaced from the pivot point of the lever and being connected to the door by a resilient connection, the pivot point of said connecting member to the lever being located at one side of the pivot point of the lever when the lever is in 55 unlocking position and being located at the opposite side of the pivot point of the lever when the lever is in locking position.

3. In combination a silo door movable between open and closed positions relative to a door frame, means for locking the door in closed position and in firm contact with the door frame, said means comprising a pivoted lever, a member for connecting said lever to the door and being pivoted to said lever at a point spaced from the pivot point of the lever, the pivot point of said connecting member to the lever being located at one side of the pivot point of the lever when the lever is in unlocking position and being located at the opposite side of the pivot point of the lever when the lever is in locking position.

4. In combination, a silo door member movable between open and closed positions relative to a door frame member, means for locking the door member in closed position and in firm contact with the door frame member, said means comprising a pivoted lever carried by one of said members, a resilient connection between the member which carries said lever and the other member, said resilient connection including a hook member and a resilient rod carried by said door member, said hook member being pivoted to said lever at a point spaced from the pivot point of the lever, the pivot point of said hook to the lever being located at one side of the pivot point of the lever when the lever is in unlocking position and being located at the opposite side of the pivot point of the lever when the lever is in locking position, said hook member being of such length that said rod will be sprung when the lever is in locking position so that the resilient force produced thereby tends to hold the lever in locking position.

5. In combination, a silo door member movable between open and closed positions relative to a door frame member, means for locking the door member in closed position and in firm contact with the door frame member, said means comprising a pivoted lever carried by one of said members, means for connecting the member which carries said lever to the other member, said means comprising a connecting member pivoted to said lever at a point spaced from the pivot point of the lever, the pivot point of said connecting member to the lever being located at one side of the pivot point of the lever when the lever is in unlocking position and being located at the opposite side of the pivot point of the lever when the lever is in locking position.

6. In combination, a silo door member movable between open and closed positions relative to a door frame member, means for locking the door member in closed position and in firm contact with the door frame member, said means comprising a pivoted lever carried by one of said members, means for connecting the member which carries said lever to the other member, said means comprising a connecting member pivoted to said lever at a point spaced from the pivot point of the lever, the pivot point of said connecting member to the lever being located at one side of the pivot point of the lever when the lever is in unlocking position and being located at the opposite side of the pivot point of the lever when the lever is in locking position, and resilient means forming a part of said connecting means for permitting movement of said lever between unlocking and locking positions, said last-named means tending to maintain said lever in locking position.

7. In combination, a stave silo comprising a plurality of vertically disposed staves, a doorway, a door frame in said doorway, means for securing said staves and the door frame in cooperative relation, said means comprising a hoop member extending substantially around the silo but terminating at the sides of the doorway, one end of said hoop being secured to a bracket fastened to one side of said door frame and the other end of said hoop being secured to a bracket fastened to the other side of said door frame, and a tie rod extending across said doorway and serving in effect to tie the ends of said last-named hoop member together, said tie rod having a head on one end and one of said brackets having an open-ended slot into which

- said end of said tie rod may be positioned, the other end of said tie rod having a nut threaded thereon and said end of said rod projecting through a closed slot formed in the other of 5 said brackets, the last-named bracket being so shaped that the portion having the slot therein comprises a horizontal portion and a vertical portion.
8. In combination with a door frame for silos 10 comprising vertically extending members, a reinforcing member extending across the door frame, said member being a tie rod, a bracket secured to each of said vertically extending members and being disposed opposite each other,

one of said brackets having a slot formed therein into which one end of the tie rod projects, said tie rod having means on said end for preventing movement of the tie rod through the slot in one direction, the other of said brackets 5 having a slot formed therein for receiving the other end of said tie rod, means on said end of said rod for preventing movement of the tie rod through said slot in one direction, said last-named bracket being so shaped that the portion 10 having the slot therein comprises two portions substantially at right angles to each other.

CHARLES A. BANGERT.
